UNITED STATES PATENT OFFICE

JAMES PEEBLES, OF DALRYMPLE, SCOTLAND, ASSIGNEE, BY MESNE ASSIGNMENTS, TO THE DORR COMPANY, INC., OF NEW YORK, N. Y., A CORPORATION OF DELAWARE

APPARATUS FOR CLEANING SAND FILTER BEDS AND THE LIKE

Original No. 1,748,898, dated February 25, 1930, Serial No. 301,655, filed August 23, 1928, and in Great Britain August 23, 1927. Application for reissue filed January 5, 1931. Serial No. 506,765.

This invention relates to apparatus for cleaning sand or other comminuted material in filter beds and the like and has for an object to provide means whereby the dirty and 5 heavily coated sand or the like forming the upper stratum of the bed may be effectively cleaned independently of the body sand, thus preventing the formation of cracks, mudballs and clogged areas at the surface of the bed.

10 In a sand filter bed which is cleaned by agitation with air and/or water introduced from an under drain the upper stratum of the bed is so remote from the region of agitation that it is not completely broken up and often coagulates, to form clogged areas liable to occasion surface cracks and crevices so that when filtration is restarted the water traverses the cracks and crevices in consequence of which the filtration efficiency of the bed is impaired 15 by reduction of effective filtration areas.

Apparatus according to the invention includes a structure movable on the filter bed or the like and sustaining means for scooping up the surface of the sand or the like. Also it 20 may include means for impelling jets of water against the sand or the like so scooped up, and impact-receiving means on which the jets of water admixed with sand or the like impinge whereby coagulated masses of sand or 25 the like are disintegrated.

The movable structure may be constituted by a motor operated carriage travelling on rails and having a grit scraper depending therefrom. The motor may operate a pump 30 on the carriage and may serve also to propel the carriage. The delivery side of the pump being in communication with a conduit suspended from the carriage and fitted with nozzles for directing against sand scooped up by 35 a scoop also suspended from the carriage jets of water delivered by the pump.

The impact-receiving means may be constituted by a plate or deflector also suspended from the carriage and presenting concavities 40 in register with the nozzles.

Impurities in the surface sand may be 45 swept towards drains while clean water enters the bed, the travelling apparatus sustaining a partition between the clean and the dirty water sections.

For cleaning filters of the pressure type the cleaning apparatus may be mounted for rotation on a vertical axis.

In the accompanying drawings Fig. 1 is a vertical longitudinal section showing a filter 55 bed clearing apparatus; Fig. 2 is a vertical section at right-angles to Fig. 1; Fig. 3 is a fragmentary detail view of the cleaning apparatus drawn to a larger scale; Fig. 4 is a fragmentary detail plan view, part horizontal section of the apparatus shown in Fig. 3; Fig. 5 is a view similar to Fig. 3 showing a slightly modified construction.

Referring to the drawings, 1 denotes each of a battery of juxtaposed rectangular filter 60 beds or chambers each having side walls 2 and end walls 3 (Fig. 1).

Adapted to run on rails 4 laid on top of the side walls 2 is a wheeled carriage 5 carrying a pump 6 and driving motor 7, which pump is adapted when in operation to draw water by way of a suction pipe 8 (Fig. 2) from one filter bed and to discharge said water by way of a flexible pipe 9 to a pipe 10 extending transversely of the adjoining filter bed and 75 fitted with spaced renewable nozzles 11.

The pipe 10 is spaced forwardly of and carried by a transverse bar 12 connected by arms 13 to the rear axle 14 of the carriage 5, the pipe 10 and bar 12 being adapted to be swung about 80 the axis of said axle 14 by means, not shown, whereby they may be moved into and out of operative position as required.

The bar 12 is formed with spaced orifices 85 each of which is disposed opposite a nozzle 11 and fitted with a renewable bush 15 presenting a convergent opening 18.

Secured to the lower face of the bar 12 is an inclined scoop plate or blade 16 adapted, when the bar is lowered into operative position, to dig into the surface of the sand as shown in Figs. 1, 3, and 5. The blade 16 is elongated and extends crosswise of the chamber. It may extend from side wall to side wall to scrape the latter as shown in Figure 2.

Spaced from the bar 12 and carried thereby is an impact plate or deflector 16' presenting concavities 17 facing the delivery openings 18 presented by the bushes 15.

In the modified construction shown in Fig. 100

5 the bar 12 and the impact plate 16' are surmounted by wall plates 19, 19' defining a channel passage 20, the upper edge of the plate 19' being slightly higher than the upper edge of the plate 19.

6 In operation, to effect cleaning of a filter bed, the pipe 10 and arm 12 are lowered into operative position with the scoop plate or blade 16 digging into the surface of the sand, 10 the pump 6 is started and the carriage is traversed slowly in the direction indicated by the arrow A from the front to the rear end of the filter bed. The jets of water issuing from the nozzles 11 carry the sand scooped 15 up by the plate 16 through the openings 18 and cause it forcibly to impinge on the concave faces 17 of the impact plate 16' whereby the coagulated masses of surface sand are thoroughly disintegrated, the sand falling on 20 to the surface of the bed through the gap between the bar 12 and the plate 16'.

It will be understood that in the forward movement of the apparatus, i. e., movement in the direction indicated by the arrow A, 25 impurities contained in the surface sand are swept towards the filter bed drain 21 by means of the blade 16 impelled by the carriage 5 (Fig. 1), clean water entering by way of the inlet 22 positioned at the opposite end 30 of the filter bed.

In the construction shown in Fig. 5 the wall plates 19, 19' form a partition between the clean water section and the dirty water section, the plate 19' being located on the clean 35 water side so that in the forward movement of the apparatus the only escape for the clean water is over the upper edge of the plate 19' or past the ends of the apparatus.

When the carriage has reached the rear end 40 of the filter bed the pipe 10 and arm 12 may be swung upwardly clear of the bed and the carriage moved back to the front end of the bed ready for another cleaning traverse.

In order that one apparatus may serve a 45 battery of filter beds there is provided a bogie 23 (Fig. 1) adapted to run on rails 24 extending transversely of the filter beds, said bogie carrying rails 25 adapted to be brought into register with the rails 4 so that the carriage 5 50 may be run back on the bogie 23 and transported to a position opposite another filter bed.

In the case of an end filter the pump 6 may draw water by way of the pipe 8 from a 55 trough disposed alongside the filter bed.

As will be understood, after the upper stratum of the bed has been cleaned by the apparatus described the body sand may be washed with ease by agitation with air and/or water, it being readily understood that the surface of the sand then presents an equitable area for passage of the air and water.

While I have described a device useful for 60 cleaning filter beds, it may be used in any

other place where a gritty deposit is desired to be treated by sweeping it toward one end of the containing chamber.

Claims:

1. Apparatus for cleaning sand or other 70 comminuted material in filter beds, including a carriage movable over said beds, a bar sustained by said carriage and presenting convergent openings, a scoop fitted to said bar for scooping up the surface, of the comminuted bed material, a pump sustained by said carriage, a connection for leading water from one of said beds to said pump, a pipe connected to the delivery side of said pump, nozzles fitted to said last mentioned pipe in register with said convergent openings and an impact plate sustained by said bar on the opposite side of said scoop from said nozzles.

2. Apparatus for cleaning sand or other 75 comminuted material in filter beds including a carriage movable over said beds, a bar sustained by said carriage and presenting convergent openings, a scoop fitted to said bar for scooping up the surface of the comminuted bed material, a pump sustained by 80 said carriage, a connection for leading water from one of said beds to said pump, a pipe connected to the delivery side of said pump, nozzles fitted to said last mentioned pipe in register with said convergent openings and 85 wall plates sustained by said bar and defining a partition separating the water above the cleaned comminuted material and the water above the comminuted material to be cleaned.

3. Apparatus for cleaning sand or other 90 comminuted material in a filter bed having an outlet at one end, including a carriage 95 movable over said bed towards said outlet, a bar sustained by said carriage and presenting convergent openings, a scoop fitted to said bar for scooping up the surface of the comminuted bed material, a pump sustained by said carriage, a connection for leading water to said pump, a pipe connected to the delivery side of said pump, nozzles fitted to said last 100 mentioned pipe in register with said convergent openings and a pair of wall plates sustained by said bar and defining a partition separating the water above the cleaned comminuted material and the water above the comminuted material to be cleaned, the wall plate remote from said outlet extending to a 105 higher level than the wall plate nearer said outlet.

4. Apparatus for use in a rectangular sedimentation chamber having side walls, end walls, an end outlet, and a bottom for supporting a gritty deposit, comprising a carriage reciprocable above the bottom of the chamber, an elongated blade extending crosswise of the chamber for scraping the gritty deposit, said blade being so mounted upon 110 said carriage that it extends forwardly under the carriage, whereby movement of the car- 115

riage forwardly impels the blade against the grit on the chamber bottom.

5. Apparatus for use in a rectangular sedimentation chamber having side walls, end walls, an end outlet, and a bottom for supporting a gritty deposit, comprising a carriage reciprocable above the bottom of the chamber, an elongated blade extending crosswise of the chamber for scraping the gritty 10 deposit, said blade being so mounted upon said carriage that it extends forwardly under the carriage, and at an angle thereto, whereby movement of the carriage forwardly pushes the blade against the grit on the chamber bottom.

6. Apparatus of the class described comprising a rectangular chamber through which liquid having gritty solids therein is adapted to flow, which chamber is provided with a 20 liquid inlet at one end, and a liquid outlet at the other end, a reciprocable carriage straddling said channel transversely, means supported on the said carriage to propel gritty solids settled from said liquid along the bottom of said channel toward said outlet end, said means comprising a scraper blade extending transversely of said channel and pivotally supported from said carriage, and means for positioning said scraper blade toward 25 said channel bottom into settled solids-propelling position, and for retracting said scraper blade away from said bottom into non-scraping position, whereby said blade on one stroke of said carriage may be made to 30 scrape settled solids along the channel bottom and on the return stroke of said carriage, not to engage any settled solids.

7. In an apparatus of the class described, the combination of a plurality of rectangular 40 sedimentation chambers having side walls, end walls, an end outlet, and a bottom for supporting a gritty deposit, comprising a carriage reciprocable along the pair of side walls, an elongated blade extending crosswise 45 of said carriage and so mounted on said carriage as to be positionable near the bottom of said chamber for scraping gritty deposit and to be capable of being raised above the level of said side walls, and a truck mounted for 50 movement transversely to said series of chambers and adapted to receive said carriage and to transport it from one to another of said chambers.

JAMES PEEBLES.
